UNITED STATES PATENT OFFICE.

CHARLES P. STEINMETZ, OF SCHENECTADY, NEW YORK, ASSIGNOR TO GENERAL ELECTRIC COMPANY, A CORPORATION OF NEW YORK.

ELECTRIC LAMP.

1,091,715.

Specification of Letters Patent: Patented Mar. 31, 1914.

Application filed May 9, 1904. Serial No. 207,023.

To all whom it may concern:

Be it known that I, CHARLES P. STEINMETZ, a citizen of the United States, residing at Schenectady, in the county of Schenectady, State of New York, have invented 5 certain new and useful Improvements in Electric Lamps, of which the following is a specification.

My present invention relates to electric 10 lamps and comprises certain improvements whereby the radiations from sources of light of different colors may be so combined and intermingled as to produce a joint product.

In carrying out my invention I combine 15 with the light from a mercury vapor lamp or lamps that derived from an incandescent lamp or lamps so as to produce a resultant illumination, practically the same as that due to white light. In order to effect the 20 combination of lights from these two sources I support the lamps within a globe of the type shown in Patent No. 563,836 Blondell and Psaroudake, July 14, 1896, and now well known under the term "holophane." 25 The effect of a globe of this character is to intermingle the lights from the two sources in such a manner that the globe appears to radiate, not the yellow light of the incandescent lamps or the greenish white light of 30 the mercury lamp, but a light which is a combination of the two and which by a proper relative proportion of the two sources approaches in character ordinary day-light.

The features of novelty which characterize 35 my invention are pointed out with particularity in the appended claims. The invention itself, however, will be better understood by reference to the following description taken in connection with the accompanying drawings, in which,

Figure 1 represents, by way of illustration, one of the numerous embodiments which my invention may assume in practice. In this figure the lamp is shown in its completed form. Fig. 2 is a view partly in cross section of the lamp, and Fig. 3 is a view of a portion of the lamp-supporting frame work.

The light-dispersing globe in which the 50 electric lamps are located, may, of course, assume various forms. In the drawing, however, the particular form shown at 1 is somewhat acorn-shaped, although in general it may be said that the prisms surround 55 the lamps through a solid angle of more

than 180°. The upper portion of the globe is provided with a flange 2 which rests on a ring 3. This ring is provided with three or more hooks as at 4, which serve as a means of engagement for supporting chains as 5 60 and 6 whereby the lamp is suspended from any suitable point.

The mercury lamp which I locate in the globe, may, of course, be of any one of a variety of types. One form, however, which 65 is found effective is shown in Fig. 2. It consists of an exhausted tube 7 inclosing suitable electrodes such as the graphite anode 8 and the mercury cathode 9. A carbon filament 10 extends from the anode and, when 70 the lamp is not running, engages at its lower end a floating armature 11. This armature is hollow at its top and carries mercury into which the lower end of the filament dips.

The lamp tube 7 is surmounted by a bulb 75 or enlargement 12 constituting a condensing chamber. This bulb affords a means for supporting the weight of the lamp, and to this end rests upon the sides of a circular opening in a plate 13 of insulating material. This plate in turn is carried by two uprights 14 and 15 secured to a frame work shown perhaps best in Fig. 3. In this figure it will be seen that the annulus 16 is carried 80 by radial arms 17, 18 and 19 secured to the 85 ring 3. The uprights 14 and 15 are fastened to inwardly projecting arms 20 and 21 secured to the annulus 16.

The mercury lamp is supported vertically 90 as shown and extends down sufficiently so that the contracted portion 22 of the lamp tube projects below the end of the globe 1. This contracted portion is surrounded by a solenoid 23 which, when energized, operates upon the float to submerge the same. The 95 initial arc produced at the lower end of the filament 10, upon the recession of the float, operates to start the lamp in a well-understood manner. The solenoid 23, with its 100 protecting casing 24, is centered in a circular opening in the lower end of the globe 1 and is supported by rods 25 and 26 depending from the arms 20 and 21.

A number of ordinary incandescent lamps, 105 in this case of the co-called bung-hole type, for example, indicated at 27, 28 and 29, are grouped about the mercury lamp. These are supported from sockets 30, 31 and 32 carried by the annulus 16. Suitable electrical connections are made whereby the lamps 110

operate in multiple with each other and so that the total current traversing the lamps flows also through the mercury lamp. The incandescent lamps therefore serve as the 5 steadyng resistance for the mercury lamp and, at the same time, by themselves giving out light, serve to raise the light-giving efficiency of the current expended in the system.

10 In making connections it is preferable that the ring 3 should not be alive, or in other words should not be connected to an active portion of the circuit. To this end the arms 17, 18 and 19 should be insulated from the 15 annulus 16, as for example by means of insulating bushings 33 and 34. A similar bushing not shown is provided for the arm 17.

When the apparatus is in operation the 20 light given off from the incandescent lamps and the light produced by the mercury lamp, in passing through the holophane globe 1, are combined and intermingled in a manner to render their joint product far superior in 25 illuminating effect to that which would exist without the use of a globe of this character. In observing the globe when thus lighted up, the individual lamps, either mercury lamps or the incandescent lamps, are not distinguishable. On the contrary, the globe appears 30 to be filled with a glowing light of a color neither that of the incandescent lamps nor of the mercury lamps but of a combination of the two which closely approaches 35 day-light.

I may if desired surmount the lamp by means of a companion holophane globe, or if desired have a double reflecting prism reflector as at 35 which reflector serves to 40 throw down the upwardly-extending radiations from the lamps. This reflector may be carried by inwardly-projecting thumbscrews as 36, 37 and 38 passing through an

ornamental protecting hood 39 surrounding the condensing chamber 12 of the mercury 45 lamp. This hood may be in two parts the upper portion of which is removable if desired.

It is evident that numerous other changes may be made in the embodiment of my invention without departing from the spirit thereof, for which reason I do not wish to be limited to the exact details shown and described.

What I claim as new and desire to secure 55 by Letters Patent of the United States is:

1. The combination of a prismatic glass globe, a ring for supporting said globe; a mercury vapor lamp, and one or more incandescent lamps in the globe and supported 60 from said ring.

2. The combination of a globe having a flanged top, a supporting ring engaging said flange, and electric lamps of different types carried from said ring.

3. The combination of a light-dispersing globe, a centrally located mercury vapor lamp in said globe, incandescent lamps grouped about said mercury vapor lamp, and having filaments extending parallel for 70 the greater part of their length with said mercury vapor lamp.

4. The combination of a globe of prismatic glass, a mercury vapor lamp supported centrally in said globe, a plurality of incandescent lamps supported in said globe around said mercury lamp, a ring support for said globe, and a frame-work carried from said ring and supporting said incandescent lamps.

In witness whereof I have hereunto set my hand this 7th day of May, 1904.

CHARLES P. STEINMETZ.
